SEWING MACHINE ATTACHMENT

Howard C. Underwood, New York, N. Y.

Application November 12, 1934, Serial No. 752,592

2 Claims. (Cl. 112—151)

This invention relates to improved sewing machine attachments and more particularly to a combination work assembling, guiding and feeding means.

Among the principal objects which the present invention has in view are: to provide an improved combined attachment for sewing machines for assembling, guiding and feeding the work; to provide means for assembling tape with respect to another part of the work; to issue the tape or the like into the path of stitching mechanism through the feed dog; to provide guiding means for the other part of the work whereby uniform lines of stitching will be obtained upon an article, such as a collar or the like while being sewn; to provide means whereby the tape or the like will be prevented from becoming distorted as it issues from the feed dog; and to obtain other advantages and results as may be brought out in the following description.

Drawings:

Figure 1 is an end elevation of my improved combination feed dog, throat plate and presser foot as applied to a sewing machine, the sewing machine and working parts being shown in broken lines and in section;

Figures 2 and 3 are plan views shown as taken on the lines 2—2 and 3—3 respectively of Figure 1;

Figure 4 is a front elevation of the combination in working relationship shown as taken on the line 4—4 of Figure 1;

Figure 5 is a similar view in section shown as taken on the line 5—5 of Figure 1;

Figure 6 is a perspective view of the combination shown as in exploded condition; and

Figure 7 is an elevation of part of an article to which the present invention is particularly directed.

Description:

As seen in the drawings and referring more particularly to Figure 1, I have shown part of a sewing machine 10 having a needle holder 11, presser foot bracket 12, and the machine bed or work supporting table 13. It is to these several parts of the sewing machine that the present combination, namely, presser foot 14, throat plate 15 and feed dog 16, may be conveniently attached to the usual sewing machine structure as will be understood by those skilled in the art. It further is to be understood that the combination of parts 14, 15 and 16 are essential to the carrying out of the present invention, that of feeding a tape 17 flatwise to the feed dog 16 and there to issue to the underside of an article or

work, the presser foot 14 providing means for guiding and keeping the tape and article in required position while lines of stitching are applied thereto by the needles.

As seen in Figures 1, 3, 4, 5 and 6, the presser foot 14 may be conveniently attached to the sewing machine structure by suitable means, one of such means preferably being by a bolt 18 through a hole 19 provided in the vertical portion 20 of said presser foot. Projecting outwardly and downwardly towards the needles of the machine is a substantially transverse or horizontal portion 21 of the presser foot, and adjacent the outer part thereof may be provided a pair of substantially longitudinal slots or openings 22, 22 through which the needles are enabled to pass during operation.

Towards the upper part of the vertical portion 20 near one side edge thereof is provided an opening or hole receiving and holding the upper transverse part or end of a spring-like member 23. Said spring-like member preferably extends downwardly parallel to the said vertical portion 20 of the presser foot, is looped next the lower end of said portion and then extends forwardly to the outer end of the flat portion 21 where it is inserted in another hole for the purpose. In order that the spring-like member will not become displaced during operation, a cut-out portion 24 is provided in the portion 20 and extending outwardly to adjacent the outer end of the flat portion 21. Said cut-out portion provides a shoulder 25 on the vertical portion so that the spring-like member or loop thereof may securely rest thereagainst. Said spring may extend in a substantially horizontal plane in the direction of the flat portion 21 and the end of the spring bent to pass through in a downward direction through the said hole provided therefor. Said end of the spring preferably projects a distance from the bottom of the flat portion 21 to constitute a work guide as will hereinafter be described.

The throat plate 15, as will readily be understood, is preferably of a generally flat nature, and adapted to be made secure to the table or bed 13 of the sewing machine as by screws 26, 26 as seen in Figure 1, one of said screws passing through a hole in the forward part of the plate. Centrally, and extending approximately to midway of the plate from the forward end thereof, is provided a channel or groove 27 having diverging walls and of appropriate width through which the binding or tape 17 may be fed and guided to the feed dog 16 as shown best in Figures 1, 3 and 6, thereby assuring the delivery of the tape in a

flatwise condition to the other part of the work or collar blank. At the inner terminus of the groove or channel, an enlarged opening 28 is provided, said opening extending through from the 5 top to the bottom of the plate. This opening 28 is of a greater lengthwise dimension than the upper part of the feed dog projecting upwardly into said opening whereby the said feed dog may operate in a forward and backward direction during 10 operation of the machine as will be understood.

The feed dog 16 is provided with a tape-receiving and guiding channel 29 from its forward end aligning with the channel or groove 27 of the 15 throat plate, said dog channel 29 deflecting upwardly within the dog and issuing at the top of the dog intermediate the forward and rearward ends thereof preferably coincident with the position of the needle-passing holes 30. Tape feeding 20 along the throat-plate channel 27 continues without deflection into dog channel 29, is there deflected upward and issues at the mid-part of the dog upon the upper surface thereof at the precise point of stitching at which point it will 25 be noted that needles 31 stitch the tape 17 to the edge of the collar, this arrangement functioning to prevent any buckling or distortion of the work being operated upon.

In carrying out the invention, the tape 17 enters 30 the channel or groove 27 passing thence into the dog channel 29 in a flatwise condition, the channel 27 being substantially the same width as the tape. As the tape continues into the dog channel, it retains its flatwise condition and issues 35 at the top midway thereof to be juxtaposed to the edge of the collar blank or the like 32. At this particular meeting point of the tape and collar blank, the needles simultaneously operate to introduce a double line of stitching thereto. In 40 order that the collar blank being sewn be at all times in proper alignment, I have shown the downwardly projecting portion of the spring-like member 23 as juxtaposed to the edge of the collar blank 32 thereby acting as a work guide 33. Said work guide at all times will keep the edge 45 of the collar blank in proper alignment with respect to the stitching operation, and prevent the collar accidentally running from side to side. It will be noted that the top of the dog is flattened 50 at a part thereof for receiving the bottom of the work guide 33, so that the dog operating in either a forward or backward direction creates no frictional contact to interfere with either the movement of the dog or the guide.

55 Furthermore, the upper face of the dog 16 is roughened, as by cross serrations 34 therein, both in advance of the issuance of the tape and beyond the same, whereby the forward part of the dog

will engage and advance the collar blank 32 simultaneous with the frictional gripping and advancement of the tape 17 by the face of the dog. This obtains a simultaneous timing and amount of advancement of both the collar blank and the 5 tape, and positively avoids any tendency of the collar blank and tape to advance at different speeds or to bunch.

By virtue of the work guide 33, it readily will be noted that the tape 17 is sewn to the edge of 10 the collar blank or the like 32 evenly and without the possibility of the hem edges protruding adjacent the outer edge of the collar as best shown in Figure 7. The needles 31 apply even lines of 15 stitches 35 to complete the work, and in this respect we call attention to the parallelism of said stitches with respect to the edges of said work. It is preferred to have the first line of stitches, namely, the line adjacent the outer edge of the collar to be back from the edge a distance more 20 than is normal, so should there be an accidental break in any threads comprising the fabric from which the collar is constructed, sufficient material will remain along the edge, particularly in the region between the line of stitches and the extreme 25 outer edge, which will prevent any possibility of such broken threads projecting outwardly beyond the said edge.

I claim:

1. In sewing machine attachments as characterized comprising in combination a presser foot, throat plate and feed dog, said feed dog having a roughened upper face for engaging and advancing the work and having both a longitudinal and vertical feed motion, said feed dog also having 35 a smooth upwardly directed area depressed below the said roughened face, and a work guide having its lower end in constant engagement with said smooth area of the said feed dog during stitching of the work so as to be below the level 40 of the under surface of the work in use.

2. In sewing machine attachments as characterized comprising in combination a presser foot, throat plate and feed dog, said feed dog having a roughened upper face for engaging and advancing 45 the work and having both a longitudinal and vertical feed motion, said feed dog also having a smooth upwardly directed area depressed below the said roughened face, a work guide having its lower end in constant engagement with said 50 smooth area of the said feed dog during stitching of the work so as to be below the level of the under surface of the work in use, and means exerting a spring tension for holding said guide against said feed dog and rendering said guide 55 responsive to the vertical movement of said feed dog.

HOWARD C. UNDERWOOD.
